(57) **CLAIM**

The ornamental design for a clamping handle assembly, as shown and described.

DESCRIPTION

FIG. 1 is a front, top, left side isometric perspective view of a clamping handle assembly in accordance with my design. FIG. 2 is a rear, top, left side isometric perspective view of the clamping handle assembly shown in FIG. 1.

FIG. 3 is a front elevation view of the clamping handle assembly shown in FIG. 1.

FIG. 4 is a rear elevation view of the clamping handle assembly shown in FIG. 1.

FIG. 5 is a left side elevation view of the clamping handle assembly shown in FIG. 1.

FIG. 6 is a right side elevation view of the clamping handle assembly shown in FIG. 1.

FIG. 7 is a top plan view of the clamping handle assembly shown in FIG. 1; and,

FIG. 8 is a bottom plan view of the clamping handle assembly shown in FIG. 1.

The broken lines illustrate portions of the clamping handle assembly which form no part of the claimed design.
